UNITED STATES PATENT OFFICE.

ANDREW SCHALLER, OF PERRYSBURG, OHIO.

WRENCH.

No. 877,741.

Specification of Letters Patent.

Patented Jan. 28, 1908.

Application filed July 19, 1906. Serial No. 326,919.

To all whom it may concern:

Be it known that I, ANDREW SCHALLER, a citizen of the United States, residing at Perrysburg, in the county of Wood, State of Ohio, have invented certain new and useful Improvements in Wrenches; and I do hereby declare the following to be a full, clear, and exact description of the invention, such as will enable others skilled in the art to which it appertains to make and use the same.

This invention relates to wrenches, and has for its object to provide a wrench of the handle - operated sliding jaw type, having means for holding the sliding jaw at any desired point when tightening or loosening a number of nuts of the same size, thus avoiding the necessity of adjusting the wrench each time, as has heretofore been the case.

A further object of the invention is to provide a wrench of such construction that by the substitution of a suitable jaw, the wrench may be utilized as a tack or nail puller.

In the accompanying drawings—Figure 1 is a side elevation of the wrench, Fig. 2 is a vertical sectional view therethrough, and, Fig. 3 is an edge view thereof partly in section.

Referring more specifically to the drawings, the numeral 6 denotes the fixed jaw of the wrench, and 7 spaced parallel cheek-pieces, which are formed integral therewith and of resilient metal for a purpose to be hereinafter described. The nut engaging portion of the jaw 6 extends above the upper edges of the cheek-pieces, and through the said jaw is an opening 8, through which is slidably engaged the shank 9 of a sliding jaw 10. The jaw 10 is of greater width than its shank, thus forming shoulders 11, which rest upon the upper edges of the cheek-pieces 7, and the underside of the said shank is of rack formation, as indicated at 12.

Pivoted between the cheek-pieces 7, below the shank 9 of the jaw 10, is the headed end 13 of a handle 14, the said headed end of the handle being substantially circular in form, and provided at its periphery with teeth 15, which mesh with the rack teeth 12 upon the shank 9 of the sliding jaw, whereby the jaw may be moved when the handle is oscillated.

In order that the jaw 10 may be held in

one position after being adjusted to suit a series of nuts of the same size which are to be turned, a set screw 16 is engaged through an opening 17 in one of the cheek-pieces 7 and a threaded opening 18 in the other cheek-piece, at the opposite end thereof to the jaw 6, and is provided with a winged head by means of which it may be turned to tighten the grip of the cheek-pieces 7 upon the shank 9 of the jaw 10, and thereby hold the jaw against movement.

In the form of my invention shown in Fig. 5, a bifurcated sliding jaw 19 is provided, which may be engaged with tacks or nails and the handle 14 oscillated to pull or extract the same.

What is claimed is—

1. A wrench of the class described comprising a fixed jaw, spaced cheek pieces formed integral with the jaw, the said jaw being provided with a slot, a movable jaw having a stem of rack formation engaged through the slot, a handle pivoted at one of its ends between the cheek pieces and provided with teeth for engagement with the rack upon the stem portion of the movable jaw, a threaded bolt engaged through the cheek pieces at their ends opposite to the ends at which the fixed jaw is located, and a thumb nut engaged upon the threaded bolt.

2. A wrench of the class described comprising a fixed jaw, spaced cheek pieces formed integral with the jaw and extending forwardly therefrom in parallel relation, the said jaw being provided with a slot the side walls of which are coincident with the inner walls of the cheek pieces, a movable jaw having a stem of rack formation engaged through the slot, the side faces of the stem and the portion of the jaw being confined between the cheek pieces, a handle pivoted at one of its ends between the cheek pieces, said handle being provided with teeth at its said end for engagement with the rack upon the stem portion of the movable jaw, the cheek pieces being extended considerably beyond the said end of the handle, a threaded bolt engaged through the portions of the cheek pieces which extend beyond the said end of the handle, a thumb nut engaged upon the bolt, the bolt being provided at one of its ends with a head which bears against the

outer faces of one of the cheek pieces and the thumb nut being adapted to bear against the outer face of the other cheek piece to cause the cheek pieces to frictionally engage the stem portion of the movable jaw and that portion of the jaw itself which lies between the cheek pieces.

In testimony whereof, I affix my signature, in presence of two witnesses.

ANDREW SCHALLER.
